UNITED STATES PATENT OFFICE.

EUGENE P. GUTHRIE, OF DALLAS, TEXAS.

GARDEN TOOL.

Application filed August 7, 1925. Serial No. 48,848.

This invention relates to improvements in garden tools and has for an object the provision of means for removably securing a blade or the like to a handle, so that a single handle will suffice for a number of different blades or tools and thus reduce the cost of the tools.

Another object of the invention is the provision of means for removably securing the blade to the handle in a novel manner, the construction affording a tool which is efficient in use and will permit of the ready removal and attachment of blades and tools of various kinds.

With the above and other objects in view, the invention further includes the following novel features and details of construction, to be hereinafter more fully described, illustrated in the accompanying drawings and 20 pointed out in the appended claim.

In the drawings:—

Figure 1 is a fragmentary view partly in section illustrating the invention.

Figure 2 is a fragmentary perspective view with the parts separated.

Figures 3 and 4 are views of different types of blades.

Referring to the drawings in detail wherein like characters of reference denote corresponding parts, the handle of the tool is indicated at 10 and is provided at one end with a tapered ferrule 11. The tool 12 which may be of any desired type such as a subsoiler blade shown in Figure 3 or a hoe blade shown in Figure 4, is designed to be removably attached to the handle. For this purpose there is provided a coupling in the form of a shank 14 which has extending from one end a screw 15, the latter having a threaded engagement with the handle 10. A shoulder 16 is formed at the juncture of the shank and screw and this shoulder is of sufficient diameter to engage the end of the ferrule so that the edge of the latter will 40 form a wear ring or washer against which the end of the shank may tightly engage.

The opposite end of the shank is provided with a head 17 having an outer flat face 18, while extending from this face is a boss 19

of rectangular shape. A threaded stud 20 50 extends from the boss.

The blade 12 is provided with an opening 21 of a size and shape to conform to the boss 19 so that the latter may engage the walls of the opening 21 and prevent rotary movement of the blade with respect to the handle. The thickness of the blade 12 is slightly greater than the depth of the boss so that a binding nut 22 may be placed upon the stud 20 to bind against the outer face 60 of the blade and securely hold the latter in position. The nut 22 is provided with a wrench engaging portion 23 and a radially disposed blade engaging flange.

It will be apparent from the foregoing 65 description and accompanying drawings that the invention provides a simple and efficient means for removably attaching a blade or tool to a handle so that a number of different blades or tools with a single handle will 70 provide a plurality of different tools.

The invention is susceptible of various changes in its form, proportions and minor details of construction and the right is here- 75 in reserved to make such changes as properly fall within the scope of the appended claim.

Having described the invention what is claimed is:—

In a garden tool, the combination with a handle provided with a ferrule to prevent 80 splitting of the end of the handle, a shank having a threaded extension having a tapered end penetrating axially through the end of the handle with a shoulder at the base of the extension, the end of the shank 85 opposite the extension having a rectangular boss with a screw stud extending from the face of the boss, a plate having an opening corresponding in shape to fit the boss, the boss being of less thickness than the thick- 90 ness of the plate, and a nut threadedly engaging the stud to clamp the plate to a flat face at the end of the shank at a point closely adjacent the base of the boss, thereby holding the plate rigid and against turning. 95

In testimony whereof I affix my signature.

EUGENE P. GUTHRIE.
